UNITED STATES PATENT OFFICE.

CLARENCE HOFFMAN AND EDWARD P. EMERSON, OF RED LION, PENNSYLVANIA.

WOODWORKING-MACHINE ATTACHMENT.

Application filed May 8, 1928. Serial No. 276,069.

The present invention relates to an attachment to a wood working machine and has for its principal purpose to provide a structure which will assist greatly in the making of 5 molding and the like.

A number of devices used up to this time, are fastened to the spindles, and consequently any vibrations in this spindle affect the shape of the molding. It is the object of the 10 present invention to provide a rigid collar against which the piece of wood rests, thereby eliminating vibration and consequently the molding is made uniform, this with safety to the operator, who can use whatever pressure 15 sure he desires against the rigid collar, without being in danger of slipping into engagement with the knives on account of the use of a movable collar.

Another very important object of the 20 invention resides in the provision of a rigid collar through which the spindle rotates, and means whereby the rigid collar may be supported in any desired adjusted position, so that the knives may be disposed thereabove 25 and therebelow.

Another very important object of the invention resides in the provision of a gauge 30 which will function to place proper pressure on the work and which is thoroughly adjustable to accommodate the size of the work and other incidental peculiarities thereof.

A still further very important object of the invention resides in the provision of an improvement of this nature which is exceedingly simple in its construction, inexpensive 35 to manufacture and embody in the usual wood working machine, strong and durable, compact and convenient in its arrangement of parts, easy to manipulate, and thoroughly 40 efficient and reliable in operation.

With the above and numerous other objects in view, as will appear as the description proceeds, the invention resides in certain 45 novel features of construction, and in the combination and arrangement of parts as will be hereinafter more fully described and claimed.

In the drawings:

Figure 1 is an elevation of the attachment 50 embodying the features of my invention.

Figure 2 is a top plan view thereof.

Figure 3 is a vertical longitudinal section therethrough.

Figure 4 is an end view of the adjustable bracket for the guide and guard. 55

Figure 5 is a top plan view of the rigid collar.

Figure 6 is a sectional view, taken substantially on the line 6—6 of Figure 3.

Figure 7 is a perspective view of the rigid 60 collar.

Figure 8 is a perspective view of one of the keys.

Referring to the drawings in detail, it will be seen that the numeral 5 denotes the bed of 65 a wood working machine provided with the usual opening 6, through which extends the spindle 7 carrying cutting elements 8. A standard 9 rises from the bed 5, adjacent the opening 6 and is provided with a longitudinally extending groove 10. An arm 11 has a collar 12 at one end, slidable on the standard 9. A set screw 14 is threaded into the collar for adjusting a key 15 into the groove 10, so that the collar may be held at different 70 heights on the standard. The arm terminates at the other end, in a pair of diverging fingers 16. A collar 17 has portions receivable between the fingers 16 and attached thereto by means of screws 18. This collar 80 17 may be formed in different sizes and may be disposed as shown in Figure 3, so as to extend partially down into the opening 6 or may be disposed considerably above the opening, obviously by means of the adjustment 85 afforded by means 15 and set screw 14 for holding the collar 12 in different positions on the standard 9. The spindle 7 extends through the collar 17 as is clearly illustrated in dotted lines in Figure 3. 90

An arcuate guard 20 may be constructed of wood or the like and has a pair of rods 21, secured as at 22, to the ends thereof and extending in spaced parallelism as is shown in Figure 2. 95

A collar 23 is adjustably mounted on the standard 9 by means of a key 24 and a set screw 25, and has arms 26 inclining downwardly and outwardly therefrom and terminating in sleeves 27 for receiving the rods 100 21, and set screws 28 are engaged in the sleeves for engaging the rods 21, for obvious adjustment, to locate the guard means 20 in relation to the work and the spindle. A collar 28' is adjustably mounted on the upper end 105 of the spindle 9 above the collar 23, by means

of a key 29 and a set screw 30. A threaded rod 31 is disposed through a threaded aperture 32 in the collar 33 and has swivel connection 34, with the collar 23, and has a crank 35, for operation thereof.

The collar 17 is supported in a rigid or stationary manner, but may be adjusted as desired. This collar does not touch the spindle upon which the knives are attached. These 10 knives may be fastened above or below the collar. The spindle revolves through the center of this collar. With this rigid collar against which the piece of wood may rest, there cannot be any vibration, and consequently, the molding or the like will be uniform throughout its length and it will be a safer operation for the operator who can use whatever pressure he desires against the rigid collar, without being in danger of slipping into 15 the knives on account of the use of the movable collar as will be readily seen is a great danger in the common practice.

It will be further seen that the guard 20 may be placed down against the work, such 25 as the molding, to prevent undesirable vibration, and at the same time, this guard prevents the hands of the operator coming in contact with the knives. The guard 20 is obviously readily adjustable. Major adjustments may be made by the set screws 25 and 30. The set screw 30 is tightened first and then a micrometer adjustment is provided by the shaft 31 and then the set screw 25 is screwed tight, so as to prevent unnecessary vibration.

It is thought that the construction, operation, and advantages of this invention will now be quite apparent to those skilled in this art, without a more detailed description 40 thereof.

The present embodiment of the invention has been disclosed in detail merely by way 45 of example, since in actual practice, it attains the features of advantage enumerated as desirable in the statement of the invention and the above description. It will be apparent that changes in the details of construction, in the combination and arrangement of parts may be resorted to, without departing from 50 the spirit or scope of the invention herein-

after claimed or sacrificing any of its advantages.

Having thus described our invention, what we claim as new is:

1. In combination, a wood working machine bed having an opening, a spindle extending through the opening, a collar disposed about the spindle, an arm extending from the collar, a standard rising from the bed, a collar adjustable on the standard, an arm connecting the collar, an arcuate guard, rods extending from the guard, a collar on the standard having arms terminating in sleeves in which the rods are adjustable, means for holding the rods in different adjusted positions in the sleeves, means for holding the first mentioned collar in different adjusted positions in engagement with the standard, a collar on the upper portion of the standard, means for holding the last mentioned collar in different adjusted positions on the standard, a shaft screw threaded in the last mentioned collar and swivelly engaged with the third mentioned collar for affording adjustment to said third mentioned collar.

2. In combination, a woodworking machine bed having an opening, a tool spindle extending through the opening, a collar disposed about the spindle in spaced relation thereto, a standard rising from said bed, an arm extending from said collar and slidably mounted on said standard, a second collar adjustable on said standard, an arcuate guard, rods secured to the ends of said guard, a third collar adjustably connected to said standard, a pair of radially extending arms secured to said third collar and terminating in sleeves at their ends for detachably connecting with said rods, means on the second and third collars for detachably securing said collars to the standard at any desired position, and means connected with said second and third collars for moving said third collar with respect to the second collar.

In testimony whereof we affix our signatures.

CLARENCE HOFFMAN.
EDWARD P. EMERSON.
